Fig. 5

Fig. 1 is a side elevational view of a bicycle luggage carrier showing my new design; a portion of the support being broken away for convenience of illustration and the dot-dash representation of a bicycle being for illustrative purposes only;

Fig. 2 is a slightly enlarged top plan view thereof, portions of the support being broken away and omitted for convenience of illustration;

Fig. 3 is an enlarged end elevational view of the platform portion taken from the left of Fig. 2;

Fig. 4 is an enlarged cross sectional view taken on line 4-4 of Fig. 2, the supports being omitted for convenience of illustration; and

Fig. 5 is a fragmentary perspective view of the platform portion taken from the rear and right.

I claim:

The ornamental design for a bicycle luggage carrier, substantially as shown and described.
